[57] CLAIM

The ornamental design for a combined advertising card and detachable beverage coaster, substantially as shown.

DESCRIPTION

FIG. 1 is a front perspective view of a combined advertising card and detachable beverage coaster showing my new design;

FIG. 2 is a rear elevational view thereof;

FIG. 3 is a left side elevational view of FIG. 2;

FIG. 4 is an end view on an enlarged scale as seen from the top of FIG. 1; and

FIG. 5 is an end view on an enlarged scale as seen from the bottom of FIG. 1.
